RUBBER HEEL

Charles E. Lewis, Corson County, S. Dak.

Application June 22, 1939, Serial No. 280,608

4 Claims. (Cl. 36—35)

This invention relates to an improved construction of rubber heel provided with means secured in the heel and adapted to receive and be engaged by driven fastenings for securing the rubber heel to the base portion of a shoe heel to securely connect the parts and to retain the driven fastenings in fixed position so that excessive pressure on the rubber heel at points where the driven fastenings are located or excessive wear will not cause the driven fastenings to be forced inwardly and into the shoe.

More particularly, it is an aim of this invention to provide a plurality of members adapted to be molded into a rubber heel for receiving driven fastenings and for forming a base to engage the head of the fastening to retain it in fixed relationship relatively to the base portion of the shoe heel to which the rubber heel is attached.

Still another object of the invention is to provide members molded into a rubber heel and including means embedded in the heel for securing the members therein, said means being slidably connected to the members for movement relatively thereto as the rubber contracts or expands so that the yieldability of the heel will not be reduced.

A further aim of the invention is to position said members so that their base portions are countersunk slightly relatively to the inner side of the rubber heel for compressing the rubber heel against the base portion of the shoe heel when secured thereto to provide a secure and firm connection therebetween.

Other objects and advantages of the invention will hereinafter become more fully apparent from the following description of the drawing which illustrates a preferred embodiment thereof, and wherein:

Figure 1 is a bottom plan view showing a heel constructed in accordance with the invention and attached to a shoe.

Figure 2 is a longitudinal sectional view taken substantially on the plane of the line 2—2 of Figure 1.

Figure 3 is a plan view of a blank from which the connecting member, as illustrated in Figures 1 and 2, is formed.

Figure 4 is a fragmentary bottom plan view similar to Figure 1 of a slightly modified form of the invention.

Figure 5 is a longitudinal sectional view taken substantially on the plane of the line 5—5 of Figure 4, and

Figure 6 is a plan view of a modified form of

fastening member illustrated in Figures 4 and 5.

Referring more particularly to the drawing, wherein like reference characters designate like or corresponding parts throughout the different views, 10 designates generally a portion of a shoe having a sole, designated generally 11, forming a part thereof and including a heel portion 12. These parts are of conventional form and are shown merely to illustrate the application of the invention which will hereinafter be described. 10

The invention constitutes an improvement in rubber heels as shown generally at 13. The rubber heel 13 is provided with a plurality of metallic members each designated generally 14 which, as best seen in Figure 3, each comprise a 15 blank formed of metal having a central base portion 15 provided with an opening 16. Base portion 15 may be of any desired shape and is provided with a plurality of integrally formed spaced outwardly extending arms 17 having the enlarged 20 oval shaped free ends 18. Arms 17 are bent at their secured ends to positions substantially at right angles to the base portion 15 and the enlarged ends 18 are bent outwardly relatively to the arms 17 and substantially at right angles 25 thereto, as best seen in Figure 2, to form flanges. The members, thus shaped, are molded into the heel 13 with the ends 18 adjacent the center thereof and the base portions 15 disposed on the inner side of the heel in exposed position and 30 preferably slightly countersunk relatively to the inner face of the heel 13.

The members 14 may be disposed in any suitable relationship relatively to the heel 13 such as in the positions as seen in Figure 1, in dotted 35 lines.

The heel 13 is provided with a plurality of bores 19 extending therethrough each of which aligns with an opening 16 of a member 14 to receive a driven fastening 20. The driven fastenings 20 are adapted to be driven through the 40

base portion 12 of the heel in any suitable manner, as by means of a punch and the pointed ends thereof are then preferably bent over and clinched as at 21. The headed ends 22 of the driven fastenings 20 abut against the inner side 45

of the base portions 15 which are drawn inwardly by the driven fastenings 20 and into contact with the heel portion 12 to position the fastenings 20 in fixed position relatively to the portion 12. Base portions 15, being slightly counter- 50

sunk, cause the inner side of the rubber heel 13 to be compressed against the outer side of the heel portion 12 when the portions 15 are forced inwardly by the fastenings 20 and into contact

with the portion 12 so that the rubber heel 13 is 55

firmly secured to the heel portion 12 of the shoe 10.

From the foregoing it will be seen, that by means of the members 14 and the fastenings 20 a firm connection is made between heel portions 12 and 13 and the members 14 by being disposed in contact with the portion 12 when the heel 13 is attached thereto retains the driven fastenings 20 in fixed position relatively to the portion 12 so that excessive pressure on the heel 13 at any point will not force any of the fastenings 20 inwardly to cause their pointed ends to puncture an innersole, not shown, so that the pointed ends of the fastenings would be in a position to contact the heel of a wearer.

In Figures 4, 5 and 6, a slightly modified form of the invention is shown comprising a heel 13' of rubber, in which a plurality of connecting members 23 are embedded in any suitable relationship relatively to each other such as in the positions, as seen in Figure 1. Members 23 each comprise a sleeve portion 24, as best seen in Figure 6, having at one end an integrally formed annular flange 25 constituting a base portion, 25 and an opposite end 26 which is flared outwardly. A washer 27 is slidably mounted on the sleeve portion 24 and retained in engagement therewith by the flange 25 and the flared end 26.

Members 23 are adapted to be molded into the heel 13' with their flanges 25 positioned similarly to the base portions 15 of the members 14 so that said flanges 25 are in exposed position on the inner side of the heel 13' and slightly countersunk relatively to its inner face. The washers 27 are embedded in the rubber of the heel 13' and are disposed adjacent to the flared ends 26 so that the rubber between the washers 27 and the flanges 25 will retain the members 23 in proper position relatively to the heel 13'.

Heel 13' is provided with a plurality of bores 28, each of which is in alinement with the bore of a sleeve 24 to receive the headed driven fastenings 29 which are driven therethrough and through the sleeves 24 and into the heel portion 12 with their pointed ends bent over and clinched as at 30. The fastenings 29 are provided with the enlarged heads 31 sized to engage the flared ends 26 of the members 23 to move the flanges 25 of the members 23 into engagement with the heel portion 12 to thereby position the fastenings 29 in fixed position relatively to the heel

portion 12 and to compress the heel 13' into firm engagement with the heel portion 12 in the same manner as the members 14 to prevent the fastenings 29 from puncturing an innersole of the shoe and to form a firm connection between the 5 shoe and rubber heel 13'.

The flanges 25 which are embedded in the heel 13' fix the position of the members 23 relatively thereto but do not affect the cushioning operation of the rubber as the washers 27 are free 10 to slide inwardly of the sleeves 24 when pressure is placed on the heel 13' so that the rubber between the washers 27 and the flanges 25 may be compressed and yield with the remainder of the heel 13'.

Various changes in the invention may be resorted to provided they fall within the spirit and scope of the invention as hereinafter defined by the appended claims.

I claim as my invention:

1. An attachment for rubber heels comprising a spool shaped member having an enlarged end, said end being mounted in the inner side of a rubber heel with the shank and opposite end thereof extending into the heel, and a washer 25 slidably connected to the shank of said member and embedded in the heel in spaced apart relationship to the enlarged end of the member.

2. An attachment for rubber heels comprising a member embedded in an opening of a rubber 30 heel and having one end disposed adjacent the inner face thereof for engaging the base portion of the heel, said member being provided with a longitudinal bore to receive a portion of the shank of a headed fastening, the shank end of which is 35 secured in the base portion of the heel, the head of the fastening being disposed against the opposite end of said member, and a washer slidably mounted on said member and embedded in the rubber heel.

3. A device as in claim 2, the ends of said member being enlarged to retain the washer thereon.

4. An attachment for rubber heels comprising a tubular member, provided with enlarged ends, embedded in a rubber heel to receive the shank 45 of a headed fastening for securing the rubber heel to a shoe, with the head of the fastening abutting against one end of the tubular member, and a washer slidably mounted on the tubular member and embedded in the rubber heel.
